UNITED STATES PATENT OFFICE.

THEODORE SIDENSOL, OF LA CROSSE, WISCONSIN, ASSIGNOR OF ONE-HALF
TO C. L. HALSTEAD, OF SAME PLACE.

CANAL-LOCK.

SPECIFICATION forming part of Letters Patent No. 368,860, dated August 23, 1887.

Application filed April 6, 1887. Serial No. 233,951. (No model.)

To all whom it may concern:

Be it known that I, THEODORE SIDENSOL, a citizen of the United States, residing at La Crosse, in the county of La Crosse and State of Wisconsin, have invented certain new and useful Improvements in Canal-Locks; and I do hereby declare the following to be a full, clear, and exact description of the invention, such as will enable others skilled in the art to which it appertains to make and use the same.

The object of my invention is to assist heavily-laden boats leaving locks on lower level and to provide for the displacement of water in front of boats when entering locks, which enables them to leave locks on lower level and to enter them more quickly and with much less labor than by the means heretofore used.

To this end my invention consists in an improvement in a lock provided with one or more tunnels or ducts, beginning below the upper gates of the lock, continuing to overflow-chamber, and thence back to the main body of water below the lower gates, the same (for the admission of water therein) being provided with a gate operated by means of a rod which extends above the lock, and to which is attached a hand-wheel for the convenience of adjustment in opening and closing.

The reason for beginning the tunnel or duct at the upper end is to prevent boats cutting off the outlet. If the locks are made double length, it will necessitate another duct or tunnel behind the first boat.

In the accompanying drawings, forming a part of this specification, Figure 1 is a plan view of the lock; Fig. 2, an elevated sectional view of lock; Fig. 3, a side view.

Similar letters refer to similar parts throughout the several views.

40 The double arrows indicate the direction of the natural flow of water in the duct or tunnel when the boat is entering locks, and the single arrow the direction when the boat is leaving lock on the lower level.

45 In order to fully understand accompanying drawings, A represents water in lock; B, abutment; C, miter-sill; D, gates; E, wall; F, lever; G, duct or tunnel; H, elbow of duct; I, gate of duct; K, overflow-chamber; J, hand-wheel of rod, and 50 L rod.

I show in Fig. 1 rod L, which extends

above the lock and is provided with hand-wheel J. I show in Fig. 2 gate I, which hand-wheel J and rod L operate for the education and induction of water into the duct or 55 tunnel G. I also show in Fig. 2 a plan view of duct or tunnel G in connection with overflow-chamber K. When a boat is about entering lock, gate I is thrown open and the water rushes through it with such momentum 60 into duct or tunnel G that it is necessary to have overflow-chamber K to relieve or break up the column or ridge of water that forms therein.

In Fig. 3 is shown a plan view of hand-wheel J, rod L, and gate I.

The duct or tunnel G is constructed on either or both sides of lock, if necessary, in connection therewith, out of stone or other suitable material. Overflow-chamber K is a part of 70 duct or tunnel G, and is similarly constructed.

Canal-locks are constructed so as to be used to their utmost capacity. In other words, boats are made as large as they can possibly be to enter locks. The sides and bottoms of 75 each nearly touch.

When a boat is approaching lock, the boatman calls for headway, which enables the boat to enter lock quickly for about eight or ten feet. It then comes to a stop, owing to the rebound or reaction of the breaker, caused by the water being forced by boat against the upper gate, and notwithstanding the strenuous efforts of the horses it is forced back to the entrance of the lock, remaining stationary until 80 the large body of water that has been forced in front of the boat can escape. As locks are now constructed this can only be accomplished by the suction of this water under the boat and its escape at the sides thereof, which requires some time and considerable effort on the part of the horses or propelling-power. My improvement obviates this difficulty by preventing the formation of a breaker in front of the boat. As the boat is about to enter, lock-gate I is thrown open and the large body of water (which forms the breaker) passes quickly through it into duct or tunnel G, thence back into the main body of water below lower gates 85 back of boat on same level with water in lock, thereby assisting boat to enter easily.

By my improvement in the construction of

locks I am enabled to have boat enter lock in about one-third of the time required ordinarily and with very little effort.

Again, when a heavy-laden boat is leaving lock on lower level, it has the same difficulty getting out. The water must first pass in lock behind the boat before it can pass out. My improvement remedies this trouble. The gate I is opened and the water follows in after 5 the boat through duct or tunnel G (in an opposite direction from its course when boat is entering) to the same level with boat, thereby likewise assisting the same. This, however, is not the case when it enters lock from upper level, as it passes readily in, because it 15 has the combined depth of water in upper and lower level and there is room for its displacement.

As locks are now constructed, they sometimes 20 help boats out of lock by letting water in behind them from the upper level; but in dry seasons they have not water to spare. My improvement prevents this, as it utilizes all the water and prevents waste.

What I claim is—

1. The herein-described structural device for the displacement of water in front of boats when entering canal-locks and to assist heavily-laden boats leaving locks on lower level, &c., which consists of a suitable gate and operating device therefor, in combination with overflow-chamber K and duct G, which begins below the upper gate of lock and continues to overflow-chamber K, thence back to the main body of water below the lower gates, substantially as described, and for the purpose set forth. 25

2. An improvement in canal-locks, consisting of a gate operated by suitable hand-wheel and rod, in combination with duct or tunnel G and overflow-chamber K, substantially as described, and for the purpose set forth. 30

In testimony whereof I affix my signature in presence of two witnesses.

THEODORE SIDENSOL
